(57) **CLAIM**

The ornamental design for a magnetic adapter set, as shown and described.

DESCRIPTION

FIG. 1 is a perspective view of a magnetic adapter set in accordance with the present invention.

FIG. 2 is a perspective view of a first connector of the magnetic adapter set in accordance with the present invention shown removed for clarity of disclosure.

FIG. 3 is a front view of the first connector.

FIG. 4 is a back view of the first connector.

FIG. 5 is a left view of the first connector.

FIG. 6 is a right view of the first connector.

FIG. 7 is a top view of the first connector.

FIG. 8 is a bottom view of the first connector.

FIG. 9 is a perspective view of a second connector of the magnetic adapter set in accordance with the present invention shown removed for clarity of disclosure.

FIG. 10 is another perspective view of the second connector.

FIG. 11 is a front view of the second connector.

FIG. 12 is a back view of the second connector.

FIG. 13 is a left view of the second connector.

FIG. 14 is a right view of the second connector.

FIG. 15 is a top view of the second connector; and,

FIG. 16 is a bottom view of the second connector.

The broken lines show portions of the invention that form no part of the claimed design.
